UNITED STATES PATENT OFFICE.

BASCOM A. DOVE, OF DALLAS, TEXAS.

LOCK AND KEY.

1,382,826.

Specification of Letters Patent. Patented June 28, 1921.

Application filed January 8, 1920. Serial No. 350,160.

To all whom it may concern:

Be it known that I, BASCOM A. DOVE, a citizen of the United States, residing at Dallas, in the county of Dallas and State of Texas, have invented certain new and useful Improvements in Locks and Keys, of which the following is a specification.

This invention relates to new and useful improvements in locks and keys.

10 The object of this invention is to provide a lock of simple construction which requires a key which is difficult to duplicate, thereby assuring the safety of articles placed in receptacles fastened by this lock.

15 A further object is to provide a lock which requires a double operation by means of an adjustable key to unlock the same.

20 A further object is to frustrate the efforts of those who are expert in opening locks without the aid of a key or with a key of their own manufacture, the said practice being commonly known as lock picking.

25 In carrying out the invention I employ a plurality of cylinders of serried sizes each cylinder rotatably disposed within the cylinder of the next larger size and held therein by means of spring pressed transversely divided tumblers disposed transversely of the said cylinders. An adjustable key in-

30 serted into a slot in the innermost cylinder releases the tumblers by bringing the division in the said tumblers in time with the division between the cylinders, a separate adjustment being required for each cylinder 35 until the cylinder which operates the latch is released.

The invention will be more readily understood from a reading of the following specification and by reference to the accompanying drawings, in which an example of the invention is shown, and wherein:

Figure 1 is a side view in section of a device embodying the invention,

Fig. 2 is a sectional view looking down on 45 the same,

Fig. 3 is a view taken on the line 3—3 of Fig. 1,

Fig. 4 is a view taken on the line 4—4 of Fig. 1, and

50 Fig. 5 is a detail of the latch mechanism of the lock.

In the drawings the numeral 10 designates the barrel of a lock mounted within a door 11 and retained therein by means of screws

12 which pass through a transversely projecting annular flange 13 integral with the barrel and engage in the said door.

A cylinder 14 is rotatably mounted within the barrel being retained against longitudinal displacement by means of a transversely extending annular flange 15 integral with the inner end of the cylinder. Horizontally disposed transversely divided spring pressed tumblers 16 mounted transversely of the barrel engage in slots in the walls of the cylinder and retain the latter against circumferential displacement.

Rotatably disposed longitudinally within the cylinder is a core 17 having an elongated slot 18 extending longitudinally of the latter and opening on the upper surface of the same adjacent the central portion thereof. A passage 19 extends from the outer surface of the core to the slot, permitting a key 20 to enter the said passage and pass into the slot, the extremity of the key engaging within the recess 21 within the inner end of the core. Vertically disposed transversely divided spring pressed tumblers 22 mounted transversely of the cylinder walls 80 engage transversely of the core and retain the latter against circumferential displacement within the said cylinder.

A key 20 having its forward end cleft so as to form a recess 23 in the same and having the contours 24 along the face of its rearward end so shaped as to maintain the divisions in the tumblers 22 at the point of division between the core and the cylinder is inserted in the lock, thus permitting the core to rotate within the cylinder.

A rod 25 is movably disposed longitudinally within the key and is pivotally connected with a lever 26 at its outer end and has its inner end resting along the bottom 95 of the recess 23. Links 27 are pivotally attached to the said rod at their lower ends and are also pivotally connected at their upper ends to a bar 28 disposed within the recess 23. The lever 26 moves within a recess 29 within the trundle of the key, a movable shield 30 integral with the lever covering the opening to the recess 29 and preventing the entrance of obstructions into the latter. In Fig. 1 the key is shown in the 105 lock, the lever being lowered and the bar 28 being in the recess 20 in the key, and the tumblers 22 in the unlocked position. Upon

the core turning a quarter of a rotation the tumblers 16 engage in the slot 18 and arrest the rotation of the core within the cylinder. By moving the lever to the raised position 5 as shown in Fig. 2, the rod 25 is partially withdrawn and thereby raises the bar 28 above the key. The contours of the face of the bar are adapted to maintain the tumblers 16 in such a position as to bring the divisions in the tumblers at the division between the cylinder and the barrel, this permitting the cylinder to be rotated within the barrel. An annular plate 31 having countersunk lugs 32 upon its outer surface, is secured to 10 the inner end of the cylinder by means of screws 33, this being rotated by the cylinder. The lugs contact arms 34 extending laterally from a latch bolt 35 slidably maintained transversely of the barrel 10 at the inner 15 end of the latter by means of loops 36 and 37 mounted upon the said barrel, a spring member 38 acting to maintain the latch bolt in the locked position and to return the said bolt to the locked position upon the withdrawal of the key from the lock. Thus the 20 lock is maintained in a locked position at all times when the key is removed, being unlocked only when the key is inserted and the lock held in an unlocked position.

25 As shown in Fig. 5 the latch bolt retains the cylinder within the barrel against longitudinal displacement.

It is obvious that the device can be made in various sizes and degrees of strength 30 without departing from the spirit of the invention, thus adapting the same to a wide range of uses.

Particular attention is called to the fact 35 that the inner elements of the tumblers 16, have their inner ends beveled, at 39, and these beveled ends are inclined upwardly in the direction of rotation of the core 17, in the unlocking movement, when turned to the left, as shown in Fig. 3. Such inner elements are prevented from turning upon 40 their longitudinal axes, by pins 39' secured thereto, operating in radial slots 40', in the core 14, Fig. 2. It is thus seen that these beveled ends 39, serve as ratchets, and when the core 17 is turned to the left sufficiently, so that the beveled ends 39 enter the slot 45 18, the core 17 will be locked to the cylinder 14, for turning movement, to the left. When the core 17 is turned to the right, the beveled ends 19 will trip over the side wall of the slot 18, and permit the core 17 to 50 rotate with relation to the cylinder 14, the cylinder at the same time being locked against turning movement, these two operations occurring when the inner and outer 55 elements of the tumblers 16 are brought into registration. The core 17 is turned to the right until the inner and outer elements of the tumblers 17 are brought into registration, at which time the key may be removed.

By lowering the bar 28 by means of the lever 26, the key may be easily withdrawn from the lock and the latter left locked.

What I claim, is:

1. In a device of the character described, 70 in combination with a key, a lock comprising a barrel member, a cylinder rotatable within the barrel member, transversely divided spring pressed tumblers beveled at their inner ends projecting inwardly from the wall of the barrel member and movably engaging in the wall of the cylinder, a core rotatably mounted within the cylinder, a slot extending longitudinally of the core and opening along one side of the latter, transversely divided spring pressed tumblers projecting inwardly from the wall of the cylinder and movably engaging in the core, a spring pressed latch bolt slidably mounted transversely of the barrel member at the inner end of the latter, an annular plate secured transversely of the cylinder at its inner end, and lugs on the plate for operating the latch bolt. 80

2. In a device of the character described, 90 in combination with a lock, a key adapted for operating the lock comprising a handle having a recess opening from its outer edge, a lever pivoted within the recess and protruding therefrom, a slidible shield secured 95 transversely of the lever and slidably covering the opening of the recess, a shank having a groove extending longitudinally along its outer portion and a serrated face extending longitudinally along its inner portion, a 100 rod resting longitudinally along the bottom of the groove and extending longitudinally through the shank and pivoting to the lever, a serrated bar resting within the groove and links pivotally connecting the bar with 105 the rod.

3. In a device of the character described, a rotatable barrel having a set of tumbler openings formed therein, a cylinder rotatable within the barrel and having a set of 110 tumbler openings to coact with the first named set and also having a second set of tumbler openings, tumblers mounted within the set of openings in the barrel and the first named set of openings in the cylinder, a core rotatable within the cylinder and having a longitudinal slot adapted to receive the inner ends of said tumblers, said core having a set of tumbler openings for coacting with the second named set of the 115 cylinder, said core having a longitudinal key receiving opening, tumblers adapted for operation within the set of openings in the core and the second set of openings in the cylinder, a key for insertion within the longitudinal opening of the core and having a set of bits for coaction with the tumblers in the openings of the core and also having a longitudinal recess, a rod extending longitudinally within the recess and having a set 120 125 130 of openings for coaction with the tumblers in the openings of the core and also having a longitudinal recess, a rod extending longitudinally within the recess and having a set

of bits to coact with the first named tumblers, means to move the rod transversely with relation to the key, and a bolt moved by the cylinder.

5. 4. In a device of the character described, a rotatable barrel having a set of tumbler openings formed therein, a cylinder rotatable within the barrel and having a set of tumbler openings to coact with the first 10 named set and also having a second set of tumbler openings, tumblers adapted for operation within the set of openings in the barrel and the first named set of openings in the cylinder, each tumbler comprising 15 inner and outer elements, the inner element having its inner end beveled, means to prevent the inner element from turning upon its longitudinal axis, a core rotatable within the cylinder and having a longitudinal slot 20 adapted to receive the inner beveled ends of said tumblers, said core having a set of tumbler openings for coacting with the second named set of openings in the cylinder, said core having a longitudinal key receiving 25 opening, tumblers adapted for operation within the set of openings in the core and the second set of openings in the cylinder, a key for insertion within the longitudinal openings of the core and having a 30 set of bits for coaction with the tumblers in the openings of the core and also having a longitudinal recess, a rod extend-

ing longitudinally within the recess and having a set of bits to coact with the first named tumblers, means to move the rod transversely with relation to the key, and a bolt 35 moved by the cylinder.

5. In a device of the character described, as a sub-combination, a barrel, a cylinder rotatably mounted within the barrel, said cylinder having a longitudinal key receiving opening, tumblers carried by the barrel and cylinder, a key for insertion within the longitudinal key receiving opening, a longitudinally extending rod carried by the key 40 and having bits to engage with the inner ends of the tumblers, and means to move the rod transversely of the key.

6. In a device of the character described, as a sub-combination, a key having a longitudinal recess, a rod extending longitudinally within the recess and having bits, and means to move the rod transversely with relation to the key.

7. In a device of the character described, as a sub-combination, a key having a longitudinal recess, a rod extending longitudinally within the recess and having bits, links pivotally supporting the rod, and a second rod extending longitudinally of the key and 50 pivotally connected with the links.

In testimony whereof I affix my signature.

BASCOM A. DOVE.
